UNITED STATES PATENT OFFICE.

JOHN F. GAIL, OF EVANSTON, ILLINOIS, ASSIGNOR TO SIMMONS COMPANY, OF KENOSHA, WISCONSIN, A CORPORATION OF DELAWARE.

FILLING FOR MATTRESSES AND LIKE STRUCTURES.

Application filed May 26, 1924. Serial No. 715,824.

The invention relates more particularly to that class of mattresses or cushions in which the desired resiliency is secured by means of coil springs arranged within an inclosing casing. The main object of the invention is to provide improved means for effectively holding the springs in such manner that their proper relation to each other may at all times be maintained and the danger of the springs contacting or rubbing together and so producing disagreeable noises and becoming distorted, may be avoided. The invention consists in the features of novelty hereinafter described, illustrated in the accompanying drawings and particularly pointed out in the claims at the end of the specification.

Figure 1 is a perspective view of a mattress embodying my invention, portions being broken away. Figure 2 is an enlarged plan view (parts being shown in horizontal section) showing the preferred manner of arranging or grouping the springs. Figure 3 is an enlarged view in vertical section on line 3—3 of Fig. 1, through a portion of a mattress or cushion embodying the invention. Figure 4 is a detail view in side elevation of one of the springs showing the manner of connecting the same to its inclosing strip by a vertically arranged tie cord or thread, the strip being illustrated in vertical section, this view being taken upon line 4—4 of Fig. 2. Figure 5 is a detail perspective view showing the preferred manner of attaching the spring inclosing strips to the terminal coils of the springs. Figure 6 is a detail view in vertical section through a portion of the pad that incloses the mattress or cushion.

In the drawings, my invention is shown as applied to that type of mattress in which the spring inclosing casing A that is formed of ticking or like flexible material is surrounded or covered by a pad B of suitable or familiar construction. The tufting cords C of the pad B may extend through the cover b of the pad and through the walls of the casing A, as illustrated in Fig. 6 of the drawings. Certain of the tufting cords, however, are preferably extended not merely through the wall of the casing A, but also around the adjacent terminal portions d of the coil springs D, as clearly shown in Fig. 3 of the drawings.

As shown, the springs D are arranged in

rows, the springs of one row alternating or nesting with the springs of the adjacent row, as clearly shown in Figs. 1 and 2 of the drawings. In the preferred embodiment of my invention, vertically disposed strips E of flexible material, such as light canvas or the like, extend around alternate rows of the springs D. Where the ends of the strips E come together, they may be united by threads or cords F, as illustrated in Fig. 4, or by rows of heavy stitching, these cords or threads F being looped around portions of the coil springs D in order to better retain the strips in proper relation to the springs. The strips E are preferably formed with broad hemmed portions e and the height of the strips is materially greater than the length of the springs D. The hemmed edges of the strips at diametrically opposite points are folded around the terminal coils of the springs, as shown in Figs. 3 and 5, and there securely held in place by means of metal staples G. These staples G are arranged at such distances from the edges of the strips E so as to form spaces or pockets e' to receive the terminal coils d of the springs D, as clearly shown in Fig. 5 of the drawings. Preferably, the strips E at points between the springs D are drawn inward towards each other about midway the height of the strips and are there connected together, as by staples H, stitching or in other suitable manner. At points between the rows of springs D around which the strips E are shown as extended the springs D of the intermediate rows are located, as clearly shown in Figs. 1 and 2 of the drawings, and the strips E are folded around the tops and bottoms of these intermediate springs D and secured by staples G to form pockets to receive the terminal coils of such intermediate springs. At points between these intermediate springs D, the adjacent strips E are drawn together and there connected by staples H, or in other suitable manner. This serves to hold the assembly against improper lateral expansion.

By the construction thus described, it will be seen that the strips E serve to effectively hold the coil springs D in proper relative position and in such manner that the springs when in position for use cannot rub together or become interlocked under the strains to which the springs in service will be subjected.

Since the specific embodiment herein disclosed is merely illustrative of a single application of my invention, it will be understood that the scope of same should be determined by reference to the appended claims, said claims being construed as broadly as possible, consistent with the state of the art.

Having thus described my invention, what I claim as new and desire to secure by Letters Patent is:

1. A filling for mattresses and the like comprising a plurality of nested rows of coiled springs, the springs of adjacent rows being staggered, and strips of fabric interposed between adjacent rows, marginal portions of said strips being folded around the end coils of said springs, the folds of adjacent portions in the length of each strip being made alternately in opposite direction, so as alternately to engage the end coils of springs in different rows.

2. A filling for mattresses and the like, comprising a pair of parallel rows of coiled springs and a single strip of fabric interposed between the rows and having successive portions of its length alternately connected to the end coils of springs in different rows for preventing the rows from contacting.

3. A filling for mattresses and the like comprising a plurality of parallel rows of axially vertical coiled springs, the springs of each row being spaced apart and positioned in offset or staggered relation to the springs of the adjacent rows, and single strips of fabric interposed between adjacent rows, each strip being secured at spaced points to the end coils of springs in the row on one side of the strip and at intermediate points to the end coils of springs in the row on the opposite side of the strip thereby to prevent the rows from contacting, the springs in one row serving to space apart adjacent springs in the adjacent row.

4. A filling for mattresses and the like comprising a plurality of parallel rows of axially vertical coiled springs, the springs of each row being spaced apart and positioned in offset or staggered relation to the springs of the adjacent rows, and single strips of fabric interposed between adjacent rows, each strip being secured at spaced points to the end coils of springs in the row on one side of the strip and at intermediate points to the end coils of springs in the row on the opposite side of the strip thereby to prevent the rows from contacting, the springs in one row serving to space apart adjacent springs in the adjacent row, and means for connecting together adjacent strips of fabric at points between springs in the row between said strips.

5. A filling for mattresses and the like, comprising a plurality of parallel rows of axially vertical spaced coiled springs, and single integral strips of fabric interposed between adjacent rows, successive marginal portions of said strips being folded around the end coils of springs in adjacent rows to form successive pockets enclosing portions of said coils and each of said strips serving to prevent contact of adjacent rows.

6. A filling for mattresses and the like comprising a plurality of parallel rows of axially vertical coiled springs, the springs of each row being spaced apart and positioned in staggered relation to the springs of the adjacent rows, and single strips of fabric interposed between the adjacent rows for preventing contact between said adjacent rows, each strip having successive portions of each margin thereof alternately folded upon itself in opposite directions, the fold portions being united to form pockets enclosing portions of the end coils of adjacent springs in different rows, the springs in one row serving to space apart the springs in the adjacent row.

JOHN F. GAIL.
